(57) **CLAIM**

The ornamental design for a frame for a window or door, as shown and described.

DESCRIPTION

FIG. 1 is an end elevation view of a frame for a window or door showing our new design;

FIG. 2 is a perspective view thereof;

FIG. 3 is another perspective view thereof;

FIG. 4 is another perspective view thereof; and,

FIG. 5 is another perspective view thereof.

The frame for a window or door is shown with a symbolic break line in its length. The appearance of any portion of the frame for a window or door between the jagged break lines forms no part of the claimed design.
